UNITED STATES PATENT OFFICE.

JACOB FISCHER, OF EVANSVILLE, INDIANA, ASSIGNOR TO THE INDIANA STOVE WORKS, OF SAME PLACE.

DESIGN FOR AN AIR-GRADE.

SPECIFICATION forming part of Design No. 23,080, dated February 20, 1894.

Application filed December 22, 1893. Serial No. 494,484. Term of patent 7 years.

To all whom it may concern:

Be it known that I, JACOB FISCHER, a citizen of the United States, residing at Evansville, in the county of Vanderburgh and State 5 of Indiana, have invented and produced a new and original Design for Air-Grates; and I do declare the following to be a full, clear, and exact description of the same, reference being had to the accompanying drawing, 10 forming a part thereof.

This air grate is one of that class that are placed in the walls of buildings, and the one herein shown and described is of a neat and ornamental character making it very attractive.

The features of the design consist of its shape, which is rectangular in form with projections on the corners, the arrangement and form of the slots and their surrounding ornamentation.

A represents the outer face or exposed front of the grate which is rectangular in form and has corner projections as shown.

B are slots formed in its face, these slots being vertical and arranged in a number of horizontal rows, the ends of these slots being curved, as at C, and between each of the ends of the slots and at the ends of the outer ones are circular depressions D.

E are vertical ridges or ribs formed on the 30 face plate A between the slots B, and at certain points have breaks or depressions F therein. The center of the grate is flattened off and in its smooth part is a slot J.

Having described the design of my air-grate, what I claim as my invention, and desire to secure by Letters Patent, is—

The design for an airgrate substantially as herein shown and described.

In testimony whereof I affix my signature in 40 presence of two witnesses.

JACOB FISCHER.
